UNITED STATES PATENT OFFICE

MOSES G. FARMER, OF NEWPORT, RHODE ISLAND.

ELECTRO-MAGNETIC HEATING APPARATUS.

SPECIFICATION forming part of Letters Patent No. 3,23,651, dated August 4, 1885.

Application filed March 14, 1885. (No model.)

To all whom it may concern:

Be it known that I, MOSES G. FARMER, a citizen of the United States, and a resident of Newport, in the county of Newport and State 5 of Rhode Island, have invented certain new and useful Improvements in Electro-Magnetic Heating Apparatus, of which the following is a specification.

It is well known that certain changes of the 10 magnetic conditions of an iron body are attended with the development of heat more or less intense, according to the rapidity and violence of the changes. I have found that if an alternating electric current be passed through 15 a coil of insulated wire surrounding an iron core of somewhat greater length than the coil a marked degree of heat is developed in the core, greatest at its ends and diminishing toward its center. To utilize and to apply 20 to general purpose this method of developing heat is the object of my present invention. I accordingly combine with an iron bar or similar body adapted to radiate the heat developed at and near its ends a large coil of low elec- 25 trical resistance, through which I pass the current from an alternating-current machine. By this means I am enabled to convert power and electrical energy into heat in a way that for a great many purposes is extremely de- 30 sirable and useful.

I have also devised certain forms of apparatus with a view to the better radiation and application of the heat. For example, I form the core of a number of plates, between which 35 are spaces at the ends, through which a circulation of air is induced by the heat; or, if the heat is to be applied to a special purpose, such as heating water, I introduce the poles of the core into the vessel for containing the water, 40 enlarging the poles or attaching some form of plate to them in order to obtain a greater radiating-surface.

I will describe more in detail these several features by reference to the accompanying 45 drawings.

Figure 1 is a side view and part section of a simple form of heater. Fig. 2 is an end view, and Fig. 3 a top or plan view, of the same. Fig. 4 is a side view of a modified form.

Fig. 5 is a plain, and Fig. 6 a part section, of a 50 device for heating water and other fluids.

A designates a core composed of a given number of iron plates, a portion of which are of the full length of the core, and the remainder are much shorter, so that when made up 55 into a bundle air-spaces will be formed between the larger plates at the end of the core.

B is the coil, made in the ordinary way. It should be of comparatively low electrical resistance, and should be of such length as to 60 strongly magnetize the core with a given current. It may also be desirable to insulate the wire with some substance capable of withstanding without injury a considerable heat.

The relative sizes of the coil and core may 65 be greatly varied, though due regard should be had to securing the best magnetic conditions. The core should be, however, at least double the length of coil, and it may be more. It is not essential that it should be straight. 70 The form shown in Fig. 4 may be desirable in some cases, and this and many other forms may be used with the same results.

In some cases it may be advantageous to bring the poles of the core into direct contact 75 with the substance upon which the heat is to act. For example, a device for boiling water or other fluid is shown in Figs. 5 and 6. The form of core shown in Fig. 4 is here used, the ends of the cores being projected into the vessel C, preferably through the bottom, and radiating-plates D are secured to the ends of the poles. With this device but a few minutes suffice to raise a large volume of water to the boiling-point with an alternating current 80 of considerable strength.

The means by which I propose to develop heat and which I have now described are in many respects economical and in many instances exceedingly desirable. With all of the devices described I use an ordinary form of alternating-current machine, by which I avoid the necessity of using special devices for reversing the current or for producing the changes of current necessary for producing the 85 requisite changes in magnetism in the core.

What I claim as my invention is—

1. The combination, with a core of mag-

netic metal having one or both ends divided into thin plates separated by narrow passages, of a coil of comparatively large size and low resistance surrounding the middle portion of the core, as and for the purpose set forth.

2. The heating electro-magnet having a coil of comparatively large size and low resistance surrounding the middle portion of a core, composed of thin iron plates, some of which project beyond the others, the projecting ends being separated from each other by intervening spaces, as set forth.

3. The combination, with a vessel for containing a substance to be heated, of an iron

core the poles of which project into the vessel, and of a coil of low resistance surrounding the middle portion of said core, as set forth.

4. The combination, with a vessel for containing a substance to be heated, of an iron core the poles of which project into the vessel, radiating plates attached to the ends of said core, and a coil of low resistance surrounding the middle portion of the core, as herein set forth.

MOSES G. FARMER.
